UNITED STATES PATENT OFFICE.

DANA E. HARDING, OF ARLINGTON, MASSACHUSETTS, ASSIGNOR TO HARDING ENGINEERING COMPANY, OF EAST BOSTON, MASSACHUSETTS, A CORPORATION OF MASSACHUSETTS.

ROTARY GLAZING MACHINE.

Application filed August 18, 1925. Serial No. 51,007.

My present invention relates to glazing machines, and more particularly to an improved rotary glazing machine.

An important step in the process of manufacturing leather from hides and skins consists, in the case of certain kinds of leather, of burnishing or ironing the grain side of the leather so as to impart a glossy finish thereto. Heretofore this operation has been performed by mechanical means in which a rapidly reciprocating member is moved over the grain side of a sheet of leather held in position on a bed or anvil. These prior machines are objectionable from a number of standpoints, among which are, first, the excessive vibration of such machines which necessitates the strengthening and shoring of a building in which they are located to an excessive degree and such strengthening and shoring has continually to be watched and added to. Second, these machines are exceedingly dangerous as a workman sits closely adjacent to the rapidly reciprocating member and the least ill timed movement on his part is apt to result in his being struck by the moving member and injured. As a matter of fact, numerous accidents occur from this one cause and the machines have acquired throughout the various tanneries the name of "man killers". A still further objection to these machines is the fact that the leather operated on must be held in position on the bed or anvil by the workman against the pulling force exerted thereon by the rapidly reciprocating glazing tool, and if the leather is not in proper condition; that is, if it contains more than the proper amount of moisture, the glazing tool is apt to seize on the leather and drag the same out of the workman's grasp. Considerable muscular force is therefore necessary to hold the leather in position and the constant strain is apt to cause ruptures and other disorders.

In my present invention I have obviated the objections inherent in prior machines, and in carrying out my invention, I provide a glazing block holder that is rotatable on a vertical shaft in a horizontal plane, thereby eliminating all reciprocatory movement. By mounting the glazing blocks on arms rotatable about a center or on the periphery of a circular member rotatable in a horizontal plane I am enabled to provide a circular bed or work support and, by surround-

ing the periphery of the rotating member with a guard, all danger of the workman being injured by coming into contact with the glazing tool is avoided. Further, by this use of a circular bed, I am enabled to, by making the circular member of proper diameter, provide a plurality of operating positions, thus making it possible for two or more workmen to operate on different hides at one and the same time. By the outlay, therefore, of a sum necessary to acquire one machine, I am enabled to furnish the equivalent of two or more machines.

The principal object of my invention, therefore, is an improved glazing machine.

Another object of the invention is an improved rotary glazing machine.

A further object of the invention is an improved rotary glazing machine in which the glazing tools rotate about a fixed center and in a horizontal plane.

Other objects and novel features of the apparatus will appear as the description of the invention progresses.

In the accompanying drawings illustrating the preferred embodiment of my invention,

Fig. 1 is a front elevation;

Fig. 2 is a plan view;

Fig. 3 is a sectional elevation on the line 3—3 of Fig. 2, and

Fig. 4 is a sectional elevation on the line 4—4 of Fig. 3.

Referring to the drawings, 10 designates a base plate of any suitable size and dimensions and preferably substantially rectangular in form. This base plate is provided with a plurality of lugs 11 through which may pass bolts or other members for securing the same in position on the floor or foundation. Centrally located on the base plate 10 and secured thereto by bolts 12 is a substantially circular plate or base 13, and formed integral with said base 13 and diametrically arranged with respect to such base are upwardly extending members 14, these members being joined at their top to a central bearing member 15, as shown in Fig. 1. Formed integral with the base 13 and in alignment with the bearing member 15 is a centrally located bearing member 16. These bearing members 15 and 16 are provided with roller bearings 17 and thrust bearings 18, and mounted in such bearings for rotative movement is a vertical shaft 19. The shaft 19 is held against vertical movement

in the bearings 17 and 18 by a nut 20 screwed onto the bottom of such shaft, the shaft being threaded for this purpose. Secured to the shaft 19 adjacent to the lower end thereof is a worm wheel 21 which meshes with and is driven by a worm 22 secured to a shaft 23 rotatably mounted in bearing members 24 formed integral with, and extending upwardly from, one side of the circular bed 13. The shaft 23 is attached to, or may be formed integral with, the driving shaft 25 of a driving motor 26 secured in any desired manner to the base plate 10. While I have described the shaft 19 as being rotated through the medium of the worm wheel 21 and worm 22 driven from the motor 26, I may, if desired, adopt the alternative method of driving by belt, in this event attaching to the shaft 19 a pulley 27 over which may run a belt 28 leading from any suitable source of power.

Secured to the base plate 10, and preferably at the corners thereof, are upwardly and inwardly extending supports 29, these supports being of any convenient height. Secured to the top of such supports 29 is a circular ring or rim 30 substantially U-shaped in cross section, as shown in Fig. 4, and this rim 30 is provided on diametrically arranged portions with raised bed portions 31. Secured to the raised portion 31 is an arcuate shaped trough 32 in which is secured a layer of resilient material 33 such as rubber, and a plurality of layers of resilient material 34 such as leather. The assembly 32, 33, and 34 forms a work bed or anvil on which is placed the leather 35 to be glazed. The arcuate beds above referred to may be of any length, but each of them preferably occupies slightly less than one fourth of the circumference of the top of the rings 30.

Secured to the top of the shaft 19 by nuts 36 is a boss or hub 37 having formed integral therewith and diametrically arranged with respect thereto the arms 38. The overall length of the two arms 38 is slightly greater than the diameter of the ring 30, as clearly shown in Fig. 2, and the outer ends of such arms 38 are provided with a vertical channel 39, the width of this channel extending transversely of the width of the ring 30. Adjustably secured in each of the channels 39 by bolts 40 extending through slots 41 formed in the walls of such channel are blocks 42, the outer lower end of each of which is provided with an arcuate groove 43. Secured to the outer face of each of the blocks 42 by bolts 44 are blocks 45, the inner lower end of each of which is provided with an arcuate groove 46, the two grooves 43 and 46 forming a portion of a substantially circular groove extending transversely of the width of the ring 30 and in this groove is clamped a cylindrical glazing block 47,

usually and preferably of glass, although any other suitable material may be employed.

Secured to the outer periphery of the ring 30 at suitable intervals are outwardly and upwardly extending bars 49, and secured to the upper ends of these bars 49 is a ring 50, the inner diameter of the ring being slightly greater than the distance between the ends of the arms 38 and the height or length of such rings being sufficient to thoroughly shield the top and bottom surfaces of the outer ends of the arms 38 and parts carried thereby.

The operation of the apparatus is as follows, it being assumed that there will be an operator for each of the beds or anvils 31 and, assuming that there will be two operators, as shown, each of the operators will, through the usual means, have control of either the driving motor 26 or the means which controls the power connected to the belt 28 so that either operator can stop or start the machine at will. Assuming that the motor 26 is utilized to drive the machine, power is turned into such motor and the shaft 19 rotates in such a manner as to move the arms 38 in the direction of the arrows shown in Fig. 2. Each operator places a sheet of leather 35 on the work support comprised of the assembly 32, 33, and 34 by sliding the same onto such portion when the arm 38 is out of engagement therewith and, referring to Fig. 3, it will be obvious that the operator may grasp the downwardly extending portions of the leather 35 to prevent movement thereof on the elements 32, 33, and 34 when the glazing roll 47 is in engagement therewith. By grasping the downwardly extending portions of the leather 35 in such a manner as to hold the same at the point marked A in Fig. 2, it will be obvious that what may be termed the forward end of the trough 31 may be utilized as an abutment for holding the leather. Each time the glazing roll 47 moves out of engagement with the assembly 32, 33, and 34, and therefore out of engagement with the leather 35, the operator may shift the position of such leather 35 so as to bring a new portion thereof into position to be engaged by the next succeeding glazing roll 47 and this operation may be repeated indefinitely on the leather 35 or on succeeding pieces of leather.

While I have necessarily shown and described the preferred embodiment of my invention somewhat in detail, it is to be understood that I may vary the size, shape, and arrangement of parts within wide limits without departing from the spirit of the invention.

Having thus described my invention, what I claim as new is:

An improved glazing machine comprising

a base, a bearing standard secured thereto and located centrally thereof, vertically arranged bearings in said standard, a shaft rotatably mounted in said bearings, means for rotating said shaft, a hub having radially extending arms in alinement with each other formed thereon and adjustably secured to the top of said shaft, a plurality of standards on said base and extending upwardly therefrom, a circular plate mounted on the top of said standards and centrally located

with respect to the vertical shaft, a plurality of raised work beds spaced about said circular plate and secured to the top thereof, a glazing block adjustably mounted at the outer extremities of the radially extending arms, and a guard plate secured to said circular plate and enclosing the radially extending arms.

In testimony whereof, I have signed my name to this specification.

DANA E. HARDING.
